UNITED STATES PATENT OFFICE

RALPH W. SHAFOR, OF DENVER, COLORADO

APPARATUS FOR EFFECTING REACTIONS BETWEEN SUCROSE AND QUICKLIME

Application filed April 5, 1927. Serial No. 181,219.

My invention relates to apparatus for use in continuously effecting the chemical reaction between sucrose and quicklime by the method disclosed in my application for Patent No. 181,157 filed April 5, 1927.

The method is included in the process of recovering sugar from beet molasses, commonly known in the beet sugar industry as the "Steffen process" and its main object is to 10 advance and expedite at a reduced cost of operation the reactions resulting in the production of the tri-calcium saccharate

15 by a continuous feed of material subject to a continuous discharge of the resulting compound.

The improved method consists mainly in separating the two reactions that take place 20 by the intermixture of lime and sucrose, in successive stages of operation, and other distinctive features of the process are that in each of said stages, the reaction is conducted in a series of successive steps and that the supply of the reagent to the material is divided accordingly. It is an object of the present 25 invention to provide apparatus of simple construction in which the process as outlined hereinabove, may be conducted in an economical, efficient and expeditious manner.

Another object resides in the provision of novel means for the distribution of the reagent over the several units of the apparatus, which divide the operation into successive steps, and 35 still another object is found in the provisions of means to automatically proportion the quantities of molasses and water in the solution to be treated in the process and the quantity of reagent added to the solution to produce the desired reactions.

Further objects of the invention will be disclosed in the course of the following description.

45 Referring to the accompanying drawings in which like characters of reference designate corresponding parts throughout the several views,

Figure 1 represents a more or less diagrammatic plan view of the apparatus,

Figure 2, a longitudinal section of the apparatus taken on the line 2—2 Figure 1,

Figure 3, a partially sectional and partially broken end-view of one of the tanks of the series in which the process is performed,

55 Figure 4, a combined section and plan view of the tank in the planes indicated by the line 4—4 in Figure 3, and

Figure 5, a fragmentary section of the tank along the line 5—5 Figure 3.

60 Referring first to Figures 1 and 2 the molasses and water are mixed in a tank 5 in proportions determined by proper adjustment of the strokes of two pumps 6 and 7 which are operated from a common shaft 8. One of the pumps connects with a supply of the molasses and the other with a source of water supply. The pumps are of definite displacement with an adjustable stroke and in operation, the relative lengths of the strokes are adjusted so 65 as to deliver the proper proportions of molasses and water desired to produce a solution of predetermined strength.

65 It is evident that the proportioned quantities of the liquids fed to the mixing tank 70 during a determinate period of time are readily changed by varying the speed of the shaft.

The process is conducted in a series of tanks preferably arranged in tandem fashion. The first reaction of the process takes place 75 in the single tank 9 and the second reaction in two tanks 10 and 12 connected for the discharge of material from one to the other by an over-flow-apron 13.

80 Each of the tanks is divided into a number of compartments by transverse partitions 14 which terminate below the top of each tank for the overflow of solution from one compartment to another. It will be observed that the first tank of the series is thus divided into three units, one of which is wider than the others and that the other tanks are each divided into six units of equal size.

85 Each compartment is divided by partitions 15 for the circulation of the solution in an upwardly and downwardly directed course by the action of rotary centrifugal pump-impellers 16 which are mounted in the lower portions of the compartments of each tank, in connection with a common shaft 17 90

100

one into another, a tapering feed apron extending over the compartments, and drag elements for moving a reagent lengthwise of the apron.

5 2. In apparatus for producing a reaction between lime and sucrose in the manufacture of sugar, a reaction tank partitioned into successively arranged compartments flowing one into another, an appliance for feeding a reagent separately to the compartments, and an automatically weighing element for feeding the reagent to said appliance.

10 3. Apparatus for producing a reaction of lime and sucrose in the manufacture of sugar, comprising a mixing tank, a pump for feeding water to the tank, a pump for feeding molasses to the tank, a shaft having driving connections with the pumps, a reaction tank, means for feeding solution from the 15 mixing tank to the reaction tank, and an appliance for feeding a reagent to the reaction tank, driven from the shaft.

4. In apparatus for producing a reaction of lime and sucrose in the manufacture of sugar, a reaction tank divided into successively arranged compartments flowing one into another, means for feeding a sucrose solution into the tank at an end thereof, the compartment at the feed end of the tank 20 being larger than the other compartments, and means for feeding a reagent to the compartments.

5. In apparatus for producing a reaction between lime and sucrose in the manufacture of sugar, a reaction tank partitioned into successively arranged compartments flowing one into another, means for feeding a reagent to the compartments, and an automatic weighing element for feeding the reagent to 30 said means.

40 In testimony whereof I have affixed my signature.

RALPH W. SHAFOR.
